UNITED STATES PATENT OFFICE.

GEORGE CHAMPOUX, OF SALMON FALLS, NEW HAMPSHIRE, ASSIGNEE, BY MESNE ASSIGNMENTS, TO DRAPER CORPORATION, OF HOPEDALE, MASSACHUSETTS, A CORPORATION OF MAINE.

SPLITTING ATTACHMENT FOR LOOMS.

1,234,287.

Specification of Letters Patent.

Patented July 24, 1917.

Application filed August 10, 1916. Serial No. 114,278.

To all whom it may concern:

Be it known that I, GEORGE CHAMPOUX, a citizen of the United States, residing at Salmon Falls, county of Strafford, State of New Hampshire, have invented an Improvement in Splitting Attachments for Looms, of which the following description, in connection with the accompanying drawing, is a specification, like characters on the drawing representing like parts.

This invention relates to a device attached to a loom for cutting or splitting the cloth directly behind the fell into a plurality of strips. Such attachment may act to cut the cloth when it is woven in the usual manner or when it is woven in such a manner as to provide central selvage strips.

The object of the invention is to provide an attachment of this character which shall be simple and efficient in its action and insure the maintenance of the cloth in contact with the cutting edge.

Another object of the invention is to provide a cutting blade and a coöperating toothed roll mounted opposite the cutting edge of the blade and acting to maintain the cloth in contact with said cutting edge.

These and other objects of the invention will appear more fully from the accompanying description and drawings and will be particularly pointed out in the claims.

The drawings illustrate so much of a loom as is sufficient for a disclosure of the present invention. The attachment may be associated with any kind of loom and hence the mechanism of the loom itself forms no particular part of the invention.

For purposes of illustration the breast beam, sand roll and take up roll of an ordinary type of loom are illustrated, being associated with a preferred form of the invention.

In the drawings,

Figure 1 is a side elevation partially in cross section of the breast beam and immediately adjacent parts in a loom with an attachment embodying the present invention in position and showing the fabric being woven;

Fig. 2 is a top plan view of the construction shown in Fig. 1, the fabric being illustrated as being woven with a center selvage;

Fig. 3 is a side elevation of the rearward end of the attachment shown in Fig. 1;

Fig. 4 is a view similar to Fig. 3, showing a somewhat different form of the attachment;

Fig. 5 is a view in cross section taken on the line 5—5 of Fig. 4.

In the ordinary type of loom a breast beam 1 extends across the front of the loom between the side frames. In the rear of the breast beam is located upon the shaft 2 the sand roll 3 which is positively driven and acts to draw the woven cloth through the loom. From the sand roll the woven cloth passes over an idler 4 to the cloth roll 5 upon which it is wound. In Fig. 1 the fell of the cloth is indicated at 6.

The cloth may be woven in any usual and suitable manner and may be of a uniform character of weave throughout, the splitting attachment being employed in this case to split the woven cloth into a plurality of strips of the desired width. Or the cloth may be woven as indicated in Fig. 2 with one or more longitudinal strips 7 of a peculiar weave to form a sort of selvage, the splitting attachment acting in this case to split the fabric centrally of the strip 7, thus leaving a selvage at each of the opposite split edges.

The splitting attachment illustrated is secured to the breast beam of the loom and projects rearwardly over the cloth directly behind the fell. For this purpose a bracket 8 is shown secured by a screw 9 or in any other suitable manner to the breast beam. This bracket projects rearwardly slightly above the plane of the cloth.

Near its rearward end the bracket 8 is provided with a vertical transverse aperture 10. A cutting blade 11 has its shank 12 located in the aperture 10 and is adjustably secured in place by a set screw 13. By reason of this adjustment the cutting blade may be raised or lowered to present its edge in proper coöperative relation to the periphery of the plane of the cloth and in coöperative relation to the toothed roller hereinafter described. This cutting blade is provided with a sharp cutting edge 14 and the blade is so shaped and mounted that the cutting edge 14 extends at an acute angle across the plane of the cloth and in the direction of the warp. The cutting edge may be a sharp straight edge such as an ordinary knife edge, as illustrated in Fig. 3, or this edge

may be serrated or provided with fine teeth as in the case of the edge 15 shown in Fig. 4, the teeth being all cut on one side so that the blade may be easily sharpened by grinding the opposite side.

The bracket 8 extends rearwardly beyond the aperture 10 and at its rearward end is bifurcated to present the arms 16 in which is journaled, by a screw journal pin 17, a roller 18. This roller is thus mounted opposite the cutting edge of the blade and the periphery of the roller is so located with respect to the cutting edge that it presses upon the cloth, is engaged and rotated by the cloth, and acts to maintain the cloth in contact with the cutting edge, and thus secure the efficient and constant action of the blade to split the cloth.

Preferably the roller 18 is provided with peripheral teeth which catch in the cloth and insure the action of the roller. As shown in Figs. 2 and 3 there is a single circumferential row 19 of these peripheral teeth while as shown in Figs. 4 and 5 there are two slightly separated circumferential rows 20 of these peripheral teeth, the two rows being positioned one at each side of the cutting blade so that the cloth is forced down more or less at both sides of the cutting edge of the blade.

In the operation of the loom as the cloth is drawn forwardly it is drawn against the inclined cutting edge of the blade and the roller presses the cloth against the edge and

insures and maintains the contact of the cloth with the edge so that the cloth is accurately and surely split along the desired line.

One or more of these attachments are secured to the breast beam at such intervals as will result in splitting the cloth into the required number and width of strips.

Having fully described my invention, what I claim as new and desire to secure by Letters Patent is:

1. In a loom, a cutting blade, means for supporting it with its cutting edge extending at an acute angle across the plane of the cloth and in the direction of the warp, and a roller provided with two circumferential rows of peripheral teeth engaging the cloth at each side of, and acting to maintain the cloth in contact with, said cutting edge.

2. In a loom, a breast beam, a bracket secured to and projecting rearwardly from said breast beam above the plane of the cloth, a cutting blade adjustably secured to said bracket and supporting the cutting edge of the blade at an acute angle across the plane of the cloth and in the direction of the warp, and a roller journaled in said bracket and provided with two circumferential rows of peripheral teeth engaging the cloth at each side of, and acting to maintain the cloth in contact with, said cutting blade.

In testimony whereof, I have signed my name to this specification.

GEORGE CHAMPOUX.
